UNITED STATES PATENT OFFICE.

JAMES M. CHRITTON, OF ROCKY FORD, COLORADO.

AERODROME.

980,599.

Specification of Letters Patent. Patented Jan. 3, 1911.

Application filed January 28, 1910. Serial No. 540,610.

To all whom it may concern:

Be it known that I, JAMES M. CHRITTON, a citizen of the United States, residing at Rocky Ford, in the county of Otero and 5 State of Colorado, have invented a new and useful Aerodrome, of which the following is a specification.

This invention relates to aerodromes of that type known as orthopteras wherein 10 flapping wings are utilized for the purpose of elevating the machine.

One of the objects of the present invention is to provide a machine of this character wherein simultaneously movable wings 15 are mounted at the sides and an elevating plane is mounted above the center, the wings and plane working upwardly and downwardly alternately so as to alternately exert an elevating action.

20 A still further object is to provide simple means whereby movement may be transmitted from the motor to the elevating wings and plane.

A still further object is to provide improved means under the control of the aviator whereby the center of gravity can be varied at will so as to tilt the wings and plane in the direction of their length for the purpose of soaring or gliding.

30 A still further object is to provide improved means whereby the center of gravity can be shifted to meet variations in the velocity of the wind, such as sudden gusts and the like.

35 A further object is to provide improved wings and plane so constructed as to move upwardly with practically no resistance from the atmosphere while, during the reverse movement thereof, the said wings and 40 plane present broad planes through which the air cannot pass.

Another object is to provide a plane and wings having flaps designed to be so positioned during the upward movement thereof 45 as to move the machine forward, it thus being possible to propel the machine both in a forward and in an upward direction by moving the plane and wings upwardly and downwardly.

50 A further object is to provide a wing or plane which is very light in construction and which will not readily get out of order.

Another object is to provide improved means for steering the machine either along 55 the ground or while in flight.

With these and other objects in view the

invention consists of certain novel details of construction and combinations of parts hereinafter more fully described and pointed out in the claims.

60 In the accompanying drawings the preferred form of the invention has been shown.

In said drawings, Figure 1 is a front elevation of a machine embodying the present improvements. Fig. 2 is a plan view thereof, the central elevating plane being removed. Fig. 3 is a side elevation, the two wings being removed. Fig. 4 is a plan view of the body of the machine and showing the relative positions of the levers, shafts, etc. Fig. 5 is an enlarged transverse section through a portion of one of the wings. Fig. 6 is a longitudinal section through a portion of said wing. Fig. 7 is a detail perspective view of a portion of one of the flaps of the wing and showing one means of connecting the same to the supporting wire. Fig. 8 is a transverse section through a flap and showing a modified means for securing it to a wire. Fig. 9 is a view partly in section and partly in elevation of the spindle of the steering wheel and the adjoining parts. Fig. 10 is an enlarged side elevation of the driving gears and their clutches. Fig. 11 is a perspective view of one of trussed levers and a portion of the wing carried thereby. Fig. 12 is an enlarged section on the line c—d Fig. 3. Fig. 13 is an enlarged section on line e—f Fig. 3. Fig. 14 is a detail view of one of the universal joints connecting a corner post with a corner standard. Fig. 15 is an enlarged view partly in section and partly in elevation of the connections between a crank and the adjoining pitmen of the wing actuating mechanism.

Referring to the figures by characters of reference A designates the carriage of the machine, the same consisting of corner posts 1 connected at their upper ends by end and 100 side strips 2 and 3 respectively. Other suitable connections are also provided between the posts so as to make a rigid and durable structure, there being an axle 4 arranged transversely under the rear portion of the carriage and the ends of which are supported by wheels 5. Upwardly and forwardly inclined frame members 6 are secured to the sides of the carriage and those portions of these strips which are located 105 in front of the carriage frame are bowed and secured together at their outer ends. A

tubular bearing member 7 is secured upon the connected ends of these bowed portions and has a longitudinally extending slot therein, as indicated at 8. A spindle 9 is mounted to rotate within the tubular member 7 and a fork 10 is connected to the lower end of this spindle and has a wheel 11 journaled within it. The said fork is of considerable length and extends preferably from the connected ends of the strip 6 and downwardly a sufficient distance to permit the wheel 11 to coöperate with wheels 5 for the purpose of holding the carriage A normally in a horizontal position.

15 Posts 12 extend upwardly from the centers of the front and rear carriage strips 2 and are fixed relative thereto, these posts supporting a bowed longitudinally extending brace 13, the front end of which is secured in any suitable manner to the upper end of the tubular standard 7. These posts also constitute supports for the propeller shaft 14. The rear end portion of this shaft extends through a bearing sleeve 15 which is attached to and extends rearwardly from the rear post 12, the blades of the propeller being secured to the rear terminal of the shaft. These blades have been indicated at 16 and may be of any preferred type although they 20 are preferably shaped and mounted as shown in the drawings. A grooved wheel or a sprocket 17 is secured to the shaft 14 and is adapted to be driven by a belt or chain 18. This belt or chain receives motion from a 25 wheel or sprocket 19 which is normally loosely mounted on the shaft 20 of the motor 21, there being a clutch 22 by means of which the wheel or sprocket can be placed into or out of connection with the shaft 20. 30 This clutch is designed to be actuated by a lever 23 mounted upon the carriage A and which transmits motion through a rod 24 to a clutch engaging lever 25.

A gear 26 is keyed or otherwise secured 35 to the shaft 20 and meshes with a gear 27 which is normally loosely mounted on a shaft 28 journaled within the post 12 near the lower end thereof. A clutch 29 is feathered on the shaft 28 and is adapted to be actuated by a lever 30 which is connected, by means 40 of a rod 31 with the said clutch 29. By shifting the clutch into engagement with gear 27 the said gear can be operatively connected to the shaft 28 and motion therefore 45 transmitted from gear 26 through gear 27 to the shaft. A crank 32 is arranged at each end of the shaft 28 and is for the purpose 50 hereinafter set forth.

A shiftable frame B is arranged above the 55 carriage and consists of corner standards 33 located directly above the posts 1 and connected to the respective posts by means of universal joints 34. Side strips 35 connect the standards 33 at intermediate points and 60 are pivotally connected to them as shown at

36, and additional side strips 37 are pivotally connected, as at 38, to the upper portions of the standards 33. These strips 35 and 37 are parallel with the side strips 3 of the carriage A. A front connecting strip 39 is 70 pivotally attached, as at 40, to the front standards 33, and another connecting strip 41 is pivotally attached to the rear standards 33 both of the strips 39 and 41 being parallel with the front and rear strips 2 of the 75 carriage.

A shaft 42 is journaled upon the side strips 3 and is disposed parallel with the front and rear ends of said carriage, there being cranks 43 at the end of the shaft and each of which 80 has a pitman 44 mounted upon it. These pitmen are connected to the front standards 33, the connection being such as to permit the standards to swing either from front to rear or from side to side. An actuating lever 45 is secured to the shaft 42 and by means thereof the said shaft can be shifted so as to transmit motion through the pitmen 44 to the standards 33 and thus swing the standards forwardly or rearwardly with relation to the carriage A. This movement is of course permitted in view of the fact that all of the connections between the standards 85 are parallel. Any suitable means, such as a toothed segment 46, can of course be utilized 90 for locking the lever 45 in any position to which it may be adjusted.

A shaft 47 is disposed longitudinally upon the carriage A and is journaled within the cross strips 2, this shaft being provided, adjacent each end, with a crank 48 on which is mounted a pitman 49. The two pitmen extend transversely of the machine and upwardly and are pivotally connected to the standards 33 at one side of the machine, the connection between these pitmen and the standards being such as to permit the said standards to swing either laterally or from front to rear without interference. The shaft 47 is also provided with an actuating lever 50 which may be locked in adjusted position in any preferred manner as by means of a toothed segment 51 designed to be engaged by a dog carried by the lever. 100

The spindle 9 heretofore referred to has forwardly converging rods 51 and 52 extending through the upper and lower portions thereof respectively, the upper rod 51 being arranged within the slot 8 while the lower rod 52 is preferably mounted in that 105 portion of the spindle located below the connected ends of the strips 6. The two rods are connected by sections 53 of silk or other suitable fabric, the said sections being stretched between the rods and constituting the rudder of the machine. Strong cords 54 are attached to the rear end of the rudder and are passed around pulleys 55 connected to the strips 6 and thence over pulleys 56 which are supported by the upper por- 110

tions of the front posts 1. From these pulleys 56 the cords extend partly around pulleys 57 which are connected to the strips 6 at points adjacent the axle 4 and the end 5 portions of the cords are then extended transversely of the carriage A and attached to an actuating lever 58 carried by the carriage A and provided with any suitable means, such as a toothed segment 59, for 10 locking it against movement. Obviously, by shifting this lever 58 to the right or to the left motion will be transmitted therefrom through the cords 54 to the rudder so as to cause the rudder to swing about the 15 longitudinal center of the tubular standards 7. Spindle 9 and fork 10 will also be partly rotated and, when the machine is traveling along the ground, it will be apparent that the wheel 11 can thus be shifted so as to 20 properly guide it. The rudder supporting structure can be reinforced in any preferred manner, there being preferably an arrangement of guy wires 60 connecting the upper end of the tubular standard 7 with the front 25 corner post 1. Other guy wires may be located at desired points within the carriage structure so as to reinforce the same.

The parts heretofore described constitute the main body of the machine, the propelling and the steering mechanism. The means utilized for elevating the machine consists of side wings C and D and an intermediate lifting plane E. The two wings C and D are similar in construction and each 30 consists of two trussed levers 61 formed of light metal tubing or any other suitable material. The upper and lower members *a* and *b* of the lever are secured together at their ends while at intermediate points are 35 arranged spacing strips 62 and 63, the strip 62 being provided with an aperture for the reception of a wrist pin 64 located adjacent the upper end of a pitman 65. This pitman is pivotally connected as at 66 to a lever 67 40 which is fulcrumed, as at 68, on the front end of a side strip 35. A pitman 69 connects one end of this lever 67 to one of the cranks 32 heretofore mentioned. A fulcrum block 70 is secured between the inner meet- 45 ing ends of the members *a* and *b* of the lever 61 and this block has one or more openings 71 for the reception of a bearing stud ex- 50 tending from one end of the upper side strip 37. Two levers 61 are used in the construction of each wing, said levers being mounted upon the two ends of the strips 37 and each being provided with the particular connection with a crank 32, such as has been de- 55 scribed.

60 Parallel longitudinally extending ribs 72 73 and 74 are secured upon the levers 61 at right angles thereto, the said ribs extending forwardly and rearwardly beyond the levers and being connected together at their ends, 65 by cross ribs 75. The longitudinal ribs 72,

73 and 74 are bowed downwardly to a slight extent and are connected, at regular intervals, by cross wires 76 extending transversely under a series of longitudinally extending reinforcing wires 77. These reinforcing wires are secured to the cross strips 75 and to the upper members *a* of the levers 61 and are for the purpose hereinafter set forth. Each of the cross wires or cords 76 has a flap 78 of silk or any other suitable light fabric supported loosely by it, the said flaps extending throughout the width of the wing or, in other words from the strip 74 to the strip 72. The flap may be attached by threading the wire or cord 76 through the upper edge portion thereof, as shown particularly in Figs. 5 and 7, or, if preferred, tabs 79 may be extended from the upper edge portion of each flap and looped about the wire or cord as shown in Fig. 8. In either instance the flap normally hangs loosely from the wire.

Hangers 80 extend downwardly from the side strips 72 and 74 and are connected in any preferred manner as by means of wires 81 or the like extended under and parallel with the side strips 72 and 74, these hangers and connections being secured to a retaining apron 82 formed of silk or other suitable light but strong fabric, the lower edge portion of each apron being disposed below the lower edges of the flaps 78. Parallel retaining wires or cords 83 connect the side aprons at points below the wires or cords 76 and these retaining wires or cords constitute 100 abutments for the flaps 78 and serve to prevent the flaps from hanging perpendicularly. All of the flaps are normally inclined slightly to the rear. It will be apparent therefore that when the wing is 105 moved downwardly the air in the path thereof will cause the flaps to swing upwardly against the net-work made up of wires or cords 76 and 77 and the flaps, when thus elevated, will lap and form an imperforate plane through which the air cannot pass. Moreover the depending aprons at the sides of the wing serve to prevent the air from escaping laterally during this downward movement of the wing and the efficiency of the said wing is thus materially increased.

Arms 84 are extended inwardly from the bearing blocks 70 and lap, the said arms working in parallel vertical planes. The free end of each arm is connected to a hanger 85 which is pivotally attached to one of a pair of cross ribs 86 connecting the side ribs of the intermediate lifting plane E. The side ribs 87 are bowed longitudinally and are connected at their ends by cross ribs 88. The structure of this plane is similar to that of each of the wings heretofore described, there being loosely depending transversely extending flaps 89 which are 130

supported normally in inclined positions by the retaining wires or cords 90 and are designed, when the plane is drawn downwardly, to swing upwardly against a net-work of wires or cords or the like connecting the ribs.

The operation of the machine is as follows:—The aviator seats himself upon the seat 91 located upon the rear portion of the carriage A and within convenient reach of the several levers necessary in order to manipulate the different moving parts of the structure. After the motor has been started the clutch 22 is shifted so as to place the wheel 19 in operative engagement with the motor shaft whereupon motion is transmitted through the belt or chain 18 to wheel 17 and thence to the propeller shaft 14. The machine will therefore be propelled forwardly, it being supported on the ground by the wheels 5 and 11. It becomes possible to steer the machine while thus traveling over the ground, simply by shifting the lever 58 so as to transmit motion through the cords 54 to the rudder and thence to the stem 9. After the machine has been given a sufficient momentum the clutch 29 can be shifted so as to connect the gear 27 with shaft 28. The cranks 32 will therefore be rapidly rotated and the pitmen 69 given an oscillatory movement so, as to work the levers 67 upon their fulcrums. Motion will therefore be transmitted from these levers to the pitmen 65 and to the levers 61 and 63 which will therefore be set in motion. During the upward movement of the wings C and D, the arms 84 are swung downwardly and therefore pull downwardly on the intermediate plane E. The flaps carried by the frame of said plane will therefore swing upwardly against the wire network and prevent the air from passing through the plane. The said plane will therefore operate to elevate the entire machine and when it reaches the limit of its downward movement such as described, the wings C and D, which have been elevated during such movement, will begin to move downwardly. The flaps carried by these wings will act in the same manner as the flaps of the plane E and said wings will therefore operate to elevate the entire machine during the downward movement of the intermediate plane. It will thus be seen that the plane and the wings operate alternately so that a continuous upward movement of the machine is produced thereby. If the propeller is in motion the machine will be driven forward during this upward movement and the flaps will tend to lie close to the wires 76 so that by stopping the movement of the wings and the intermediate plane, the machine can be caused to soar after the manner of an ordinary aeroplane.

One of the principal advantages resulting

from the structure herein described is the fact that the machine is capable of hovering over a fixed point and that its rise is not dependent upon momentum imparted by the propeller. The machine is, however, capable of soaring and, if desired, the wings and the propeller can be operated simultaneously. Should it be desired to change the altitude of the machine without operating the wings and intermediate plane, the aviator may shift the center of gravity by manipulating the lever 45. Shaft 42 will therefore be rocked and will pull or push upon the pitmen 44 and cause the corner standards 33 to swing relative to the carriage. The wings and intermediate plane will therefore be shifted either forwardly or rearwardly relative to the carriage. Should the said wings and plane be shifted forwardly the weight of the carriage, etc., would of course tend to tilt them so as to elevate the front edges thereof, and the machine, during its forward movement, would then rise. The machine can also be lowered by so shifting the parts as to incline the wings and plane downwardly toward their front ends. Any sudden gust of wind meeting the machine at the sides can be off-set by shifting the weight laterally by means of the lever 50. This lever can also be used for centering the machine prior to a flight.

As shown in Fig. 6 and as heretofore stated, the flaps of the wings and plane assume inclined positions during the upward movement thereof, the said flaps resting against the cords or wires 83 and 90. It will be apparent therefore that during the movement of the plane E and the wings C and D, these flaps will present inclined faces to the air and thus cause the machine to be propelled forward to a slight extent during each upward movement of the plane E and wings C and D. Obviously therefore the vertical reciprocation of the wings and plane can be used to propel the machine forward as well as to elevate it, without the necessity of utilizing a propeller 16.

It is of course to be understood that various changes may be made in the construction and arrangement of the parts without departing from the spirit or sacrificing any of the advantages of the invention as defined in the appended claims.

What is claimed is:—

1. In an aerodrome, an elevating element comprising a frame, said frame being bowed in the direction of its length, flexible flaps loosely supported within and extending below the frame, the width of each flap being greater than the distance between two adjoining flaps, aprons fixedly connected to and depending from the sides of the frame, means connecting the aprons for limiting the downward movement of the flaps relative to the frame, and means secured to the

- frame for limiting the upward movement of the flaps relative thereto.
2. An aerodrome including a carriage, side wings connected thereto and extending 5 beyond the sides thereof, an intermediate elevating plane interposed between and above the wings, a motor upon said carriage, and means operated by the motor for simultaneously reciprocating the plane and oscillating the wings in opposite directions to 10 elevate the carriage.
3. An aerodrome including a carriage, standards connected thereto, means for shifting the standards forwardly or rearwardly 15 relative to the carriage, means for shifting the standards laterally relative to the carriage, and elevating means above, and movably connected to said standards said means including side wings mounted for up and 20 down oscillation, and an intermediate plane mounted for up and down reciprocation, said plane being movable in one direction during the movement of the wings in the opposite direction.
- 25 4. An aerodrome including a carriage, standards connected thereto by universal joints, elevating elements connected to the standards, rock shafts mounted on the carriage, separate means for actuating the respective shafts, connections between each shaft and certain of the standards for swinging all of the standards in the direction of the length of the carriage, and connections 30 between the other shafts and certain of said standards for transmitting motion from the shaft to the standards to shift the standards laterally.
- 35 5. An aerodrome including opposed wings mounted for up and down swinging movement, means for actuating said wings, arms extending inwardly from the wings, an intermediate plane, and connections between the plane and arms, said connections and arms operating to bodily reciprocate the 40 plane in a direction opposite to the wings during the oscillation of the wings.
- 45 6. In an aerodrome, a carriage, standards connected thereto for universal movement relative to the carriage, trussed levers sup-
- ported by the standards and mounted to 50 swing in planes perpendicular to the carriage, means for locking the standards against movement relative to the carriage, frames mounted on the levers, flaps loosely connected to and normally suspended from 55 the frames, and means for actuating the levers and frames to swing the flaps within the frames, said flaps being adapted to lap during the downward movement of the frames to constitute a lifting plane. 60
7. An aerodrome including a carriage, a crank shaft mounted for rotation thereon, means for actuating the shaft, oppositely extending elevating wings above and connected to the carriage, each wing including levers, a frame upon the levers, and transversely extending flaps loosely supported within the frame, and mechanism for transmitting motion from the crank shaft to each wing, said mechanism including an intermediate lever, and pitman connections between the respective ends of said lever and the crank shaft and a lever of the wing. 65
8. In an aerodrome, an elevating element including a frame, flaps loosely supported 70 therein, aprons fixedly connected to and depending from the sides of the frame, means connecting the aprons for limiting the downward movement of the flaps relative to the frame, and means secured to the frame for 75 limiting the upward movement of the flaps, relative thereto.
9. An aerodrome including wings, an elevating plane, power transmitting connections between the wings and the plane, means 80 for actuating the connections to simultaneously reciprocate the plane and oscillate the wings, a propeller, and means for tilting the plane and wings from front to rear relative 85 to the propeller. 90

In testimony that I claim the foregoing as my own, I have hereto affixed my signature in the presence of two witnesses.

JAMES M. CHRITTON.
